(57) **CLAIM**

The ornamental design for a archery glove, as shown and described.

DESCRIPTION

FIG. 1 is a front elevational view of an archery glove showing my new design;

FIG. 2 is a rear elevational view thereof;

FIG. 3 is a side view, taken from the left side of FIG. 1;
FIG. 4 is a side view, taken from the right side of FIG. 1;
FIG. 5 is a top plan view thereof; and,

FIG. 6 is a bottom plan view thereof.

The broken line showing a bow mechanical release in FIG. 1 is for illustrative purposes only and forms no part of the claimed design.

The broken lines shown on the wrist straps in FIG. 1 are understood to represent stitching.
